UNITED STATES PATENT OFFICE.

OSVILLE J. FRITZ, OF WEISENBURG, PENNSYLVANIA.

INSULATOR.

1,109,058.

Specification of Letters Patent.

Patented Sept. 1, 1914

Application filed August 23, 1913. Serial No. 782,329.

To all whom it may concern:

Be it known that I, OSVILLE J. FRITZ, a citizen of the United States of America, residing at Weisenburg, in the county of Lehigh and State of Pennsylvania, have invented certain new and useful Improvements in Insulators, of which the following is a specification, reference being had thereto to the accompanying drawing.

10 This invention relates to insulators, and has for its object the production of a simple and efficient means for holding the wires in their correct position without the aid of any secondary securing means.

15 Another object of this invention is the production of an insulator which is provided with a plurality of passageways which are adapted to easily receive the wires for retaining the same in their correct position.

20 With these and other objects in view, this invention consists in general of certain combinations, constructions and arrangements of parts, as will be hereinafter fully described and claimed.

25 In the accompanying drawings, Figure 1 is a side elevation of the insulator. Fig. 2 is a side elevation of the same, a portion of the insulator being shown in section. Fig. 3 is a section taken on the line 3-3, Fig. 1, looking upwardly. Fig. 4 is a section taken on the line 3-3, Fig. 1, looking downwardly.

30 Referring to the accompanying drawings by numerals, 1 indicates the insulator body having the usual threaded pocket 2 for the reception of the usual supporting pins whereby the insulator will be supported. The upper portion of this body 1 is provided with a slot 3 and a plurality of passages 4. These passages 4 are formed so as to communicate with the slot 3 and diverge toward their outer portions. The supporting base of the insulator formed adjacent the slot 3 is bowed so as to extend downwardly toward its outer portion as indicated at 5. In order to retain the wires 6

within the passages 4, there is provided a plurality of depending lips 7 which are adapted to overhang the wires. When this device is used, a wire may be easily placed 50 within the slot 3, at which time it may be moved to one side so as to rest within two of the passages 4. Since the wire rests upon the bowed portion 5, there will be formed a binding action which will cause the wire to 55 tear against a pair of lips 7 for holding the same within the passages. A wire may then be placed so as to rest within the remaining passages, whereby the two wires necessary for forming a circuit may be easily carried 60 by one insulator; since the same are provided with suitable insulation, there will not be any danger of causing a short circuit.

From the foregoing description, it will be seen that a simple insulator has been provided which will efficiently retain a pair of conductor wires without the aid of secondary securing means.

Having thus described my invention, what is claimed as new is:

An insulator comprising a body, said body provided contiguous its upper portion with an enlarged transverse slot, said body provided with a pair of diverging passages adjacent each end portion of said slot, integral 75 lips formed upon said body at the outer portions of said slot and passages, the sides of said body at the lower portion of said slot being parallel at their central portion, said slot being adapted to receive a pair of wires 80 and to allow the wires to pass outwardly through said passages and be held in said passages by said lips, the lower parallel portion of said side walls adapted to form a binding engagement with the wires thereby 85 firmly holding the wires within said slot.

In testimony whereof I hereunto affix my signature in presence of two witnesses.

OSVILLE J. FRITZ.
